UNITED STATES PATENT OFFICE.

ROSCOE F. LEVENS, OF PORTSMOUTH, RHODE ISLAND, ASSIGNEE, BY DIRECT AND MESNE ASSIGNMENTS, TO THE LEVENS MOTOR COMPANY, INCORPORATED, A CORPORATION OF RHODE ISLAND.

INTERNAL-COMBUSTION ENGINE

Application filed October 20, 1920. Serial No. 418,147.

To all whom it may concern:

Be it known that I, ROSCOE F. LEVENS, a citizen of the United States, residing at Portsmouth, in the county of Newport and State of Rhode Island, have invented certain new and useful Improvements in Internal-Combustion Engines, of which the following is a specification.

My invention relates to internal combustion engines and has for its essential objects cooling the cylinder whereby water jackets may be dispensed with; to prevent heat loss; to introduce the fuel into the cylinder chamber at a high temperature whereby a less degree of compression is required to raise the charge to the ignition point; to enable the engine to be changed in operation from a two cycle to a four cycle or other higher cycle system or vice versa; to enable this change to be effected in any piston rod engine of any number of cylinder units as well as in a single, nonopposed, and nonmultiple engine cylinder; and to effect the enumerated purposes in a compact, certain, and simple structure.

To the above ends essentially but not exclusively, my invention consists in such parts and in such combinations of parts as fall within the scope of the appended claims.

In the accompanying drawings which form a part of this specification

Figure 1 is a side elevation, partly in longitudinal section of an internal combustion engine illustrating the same in its present and preferred form of embodiment,

Figure 2, a plan view of the cylinder and adjacent parts,

Figure 3, a side elevation of the same showing a portion in section on line 3—3 of Figure 2,

Figure 4, a rear end elevation of the cylinder omitting the pulley or fly wheel.

Figure 5, a plan view of the intake cam,

Figure 6, an elevation of the same,

Figure 7, a section taken on line 7—7 of Figure 6,

Figure 8, an enlarged section taken on line 8—8 of Figure 5,

Figures 9 and 10, sections taken on lines 9—9 and 10—10 respectively of Figure 1,

Figure 11, a section on line 11—11 of Figure 2,

Figures 12 and 13, plan and side elevation respectively of the exhaust cam,

Figure 14, a section of the same on line 14—14 of Figure 13, and

Figure 15, a fragmentary side elevation of a portion of the engine opposite that shown in Figure 1.

Like reference characters indicate like parts throughout the views.

The frame of my engine may be of any construction best suited for supporting the operating parts. The form thereof herein shown comprises a base 17 carrying two supports 18 for the ends of a cylinder 19. The latter comprises an outer cylindrical wall 20, and an inner wall 21, intermediate which walls is a resultant annular cylindrical air chamber 22. The wall 21 has at its forward end oppositely disposed ports 24 leading from the chamber 22 to the piston chamber 25. The cylinder has the usual heads 26 and 27, the latter carrying the gland 28 for the piston rod 30 of the piston 31. The upper portion of the cylinder casting at each side of the air and piston chambers has laterally extended portions 34 and 35. In the front portions of these are seats 36 and 37 for poppet valves 38 and 39 respectively whose depending stems 50 and 51 are slidably mounted in the extensions and carry helical springs 52 and 53 which press at their upper ends against the extensions, and are supported at their lower ends by washers 54 and 55 fast to the stems. In the rear portions of the extensions upon seats 58 and 59 are similar valves 60 and 61 whose stems 62 and 63 slide in the respective extensions and are tensioned by springs 64 and 65 engaging the latter and washers 66 and 67 fast to the respective stems.

The rear portion of the side of the extension 34 has an intake opening 69 which in four cycle operation admits carbonized air 95 to a chamber 70 below the valve 60 and leads it through the seat 58, and through a passage 72 above said valve into the air chamber 22 where it is preheated. Thence the fuel is sucked by the piston through ports 24 in chamber 25 and is then returned by the return stroke of the piston through said ports to chamber 22 where it is slightly compressed and thence enters a chamber or passage 74 below the valve 38 and passes through this valve seat 36 and through a passage 75 above the valve leading to the piston chamber 25. The scavenging stroke

of the piston expels the products of combustion from the piston chamber through an exhaust passage 77 above the valve 39, through valve seat 37, and through a chamber 78 below the latter valve, communicating with the atmosphere through an opening 79.

In two cycle operation the fuel is drawn through the opening 69, chamber 70, passage 72, chamber 22, ports 24 into chamber 25, and returned through ports 24 into chamber 22 already described, and then enters passage 81, and passes through the valve seat 59 and a passage 83 into the piston chamber. During the up stroke the products of combustion are expelled through the passages 77 and 78 and the opening 79 as described in connection with the four cycle operation.

The fuel in its course from the carburetor through the chamber 22 cools the cylinder walls 20 and 21. In chamber 22 the fuel absorbs heat from the combustion chamber 25 which radiates from the partition 21. This absorption not only conserves heat units that would otherwise be lost but cools the cylinder partitions. The introduction of this heated fuel into the combustion chamber in front of the piston lessens the degree of heat that otherwise would be required to be generated by the forward or compression stroke of the piston.

The engine frame includes parallel guide ways 85 projecting horizontally from the forward end of the cylinder, connected by a cross bar 86 supported by a post 87 fast to the base 17. A cross head 89 of common construction on the piston rod, and sliding in the guide ways, embraces in its socket 92 the spherical head or ball 93 on a radial arm 94 fast to an arcuate yoke or segmental bar 95 journaled, through an intermediate opening 96, on an arm 98 carrying on its end a ball 99 mounted in a socket 100 in an inclined standard 101 fast to the base 17. The ball is retained in its seat by a cap 102 threaded to the standard. Integral with the lower portion of the member 95 is a radial arm 104 carrying upon its end a ball 105 movable in a socket 106 formed in a solid wheel 107 fast to one end of the main shaft 109, which carries upon its other end a fly wheel or pulley 110. The shaft 109 is journaled in bearings 111 in the supports 18. The described toggle lever mechanism converts the reciprocating motion of the piston rod to rotary motion in the main or crank shaft. The latter has fast thereto a gear 112 meshing with gears 113 and 114 on cam shafts 115 and 116 respectively, journaled at opposite sides of the cylinder in bracket arms 118 and 119 respectively. Slidably mounted on the shaft 115 is a cam member 121. In detail, as shown in Figures 5 to 8 inclusive, this member comprises a sleeve 122

provided with an internal longitudinal channel 125 to slidably receive the feather 126 seated in a longitudinal groove 127 in the shaft 115. At one end of the sleeve is a laterally extending cam shoulder 129, and at its opposite end are two diametrically oppositely disposed cam shoulders 130 and 131. The shoulder 130 is of greater longitudinal extent than the shoulder 131. Intermediate its length the sleeve 122 has an external annular groove 133 adapted to loosely receive a pin 135 in the end of a lever 136 fast intermediate its length to a rock shaft 137 journaled in walls 138 upon the supports 18 and constituting a part of the cylinder support. Pivoted at 140 to the opposite end of the lever 136 is a link 141 pivoted at 142 to an intermediate portion of an arm or hand lever 144 pivotally attached at 146 to a standard or arm 147 fastened by a screw 148 to the base 17. It will be observed that the manual movement of the lever 144 through the link and lever device longitudinally reciprocates the cam member 121 upon its shaft 115. Notwithstanding the engagement of the member 121 by the stud 135 it will be observed that such engagement does not preclude the rotation of the member 121 with the shaft 115. This is due to the freedom of the pin 135 in its transverse peripheral groove 133.

Longitudinally slidable on the shaft 116, as shown in Figures 12 to 14 inclusive, is a cam member 150 comprising in detail a sleeve 151 slidable on a feather 153 in the shaft 116. Upon one end of the sleeve is a laterally extending cam shoulder 155, adjacent which upon the sleeve are oppositely disposed cam shoulders 156. Upon the other end of the sleeve 151 are diametrically oppositely disposed cam shoulders 158. The sleeve 151 is provided with an annular groove 160 adapted to loosely receive a pin 161 upon the end of a lever 162 fast to the rock shaft 137. It will be observed that the cam members 150 have both longitudinal and rotary movement similar to that described in connection with cam members 121, and are movable in unison by the lever 144.

Lateral bosses 164, spaced from each other upon one of the supporting walls 138, have journaled therein tappet pins 165 and 166 respectively. The pin 165 is in the path of cam shoulder 129, and the pin 166 is in the paths of shoulders 130 and 131. The upper ends of the tappet pins 165 and 166 are respectively adjacent the lower ends of the valve stems 50 and 62 respectively. The bosses 168 and 169, spaced from each other upon the opposite supporting wall 138 of the cylinder, have slidably mounted therein vertical tappet pins 171 and 172 respectively. The lower end of the pin 171 is in the path of the cam shoulders 155 and 156. The pin 130

172 is adapted to engage the cam shoulder 158. Above the tappet pins 171 and 172 and adjacent the same are the valve stems 51 and 63 respectively. The shoulders upon the 5 cam members in their rotation elevate the several tappet pins and open and close the valve seats through the respective valve stems.

The engine operates either as a two cycle 10 or four cycle mechanism according to the control of the valves by the cams above described. In detail the operation is as follows.

When operating as a four cycle it will be 15 understood that the operator will slide the cam members 121 and 150 by lever 144 to such a position as to bring the cam shoulder 129 in line with tappet pin 165 and cam shoulder 130 in the path of tappet pin 166. 20 In which relative position the cam shoulder 155 will be in the path of tappet pin 171 and the tappet pin 172 will not be in engagement with any cam surfaces whatever.

When the engine is operating as a two 25 cycle structure the cam members 121 and 150 are longitudinally moved to such a position that as the valve members rotate there is no contact whatever between the valve shoulder member 129 with the tappet 165. The tappet pin 166 is, however, in the path of cam shoulders 130 and 131. In this operative cycle the cam shoulder 155 is out of contact with the tappet pin 171, but the latter is in the path of cam shoulder 156. The tappet 30 pin 172 is, however, in this cycle in the path of cam shoulder 158.

It is deemed essential that the precompression take place in the annular chamber 22 surrounding the cylinder and that this 40 chamber be cut off from communication with the crank case, it being understood that precompression in the present instance does not at any time take place within the crank case. By this means the cool gases entirely 45 surround the cylinder and tend to cool the latter and yet are preheated by the heat generated in the cylinder. Furthermore by reason of this auxiliary annular chamber 22 being shut off from communication with the 50 crank case there is no danger of leakage of the gas from the latter, as happens in the present type of two cycle engines.

The operation both as a four cycle and 55 as a two cycle engine is as follows:

As a four cycle—beginning with the carburetor the gas is taken in through the inlet valve through the auxiliary chamber 22, 60 through the passage 75 into the piston chamber following the piston on its travel towards the piston head on the compression stroke. When the piston reaches the extreme limit of its travel gases being now compressed in the cylinder, ignition takes place firing the compressed charge and 65 drives the piston outward on its working

or power stroke. This outward stroke of said piston drives the gases that are on the underneath side of the piston, that were drawn from the carburetor, back through the passage 83 into the auxiliary chamber 70 22 where it is held under precompression, the valve 38 closing while the piston is passing over the passage 83 and again, immediately opening when the piston has passed by the passage or opening 83 on its next return 75 stroke.

This valve 38 opens every other stroke of the piston when the engine is running four cycle and on every stroke when the engine is running two cycle, or it may remain open 80 all the time with the engine running two cycle.

The inlet valve from the carburetor having closed the next travel of the piston will push out the burned gases through the exhaust port 77 and the passages 78 and 79, thus scavenging the cylinder. The gases that were driven through the passage 83 back into the auxiliary chamber where they were held under precompression having followed the piston back through passage 83, re-expanding them. The piston reversing its direction will drive gases back through passage 83, precompressing them slightly, the piston continuing its outward movement 95 will uncover passage 75 permitting precompressed gases to flow from the chamber 22 into the cylinder 25. The continued outward travel of the piston will push all gases that are on the underneath side of said 100 piston through auxiliary chamber 22 leaving the chamber 25 full of combustible gases ready for compressing by the piston on its next stroke completing the four cycle operation. 105

As a two cycle—beginning with the carburetor gases flow through the inlet valve through the chamber 22, through the passage 83 and follow on the under side of the piston to the end of its inward travel. The piston on this stroke has compressed a charge of combustible gas, ignition now taking place, this charge is fired and drives the piston outward, the piston having previously drawn in a charge of combustible gas on its under side through chamber 22 and passage 83 now drives this charge of combustible gas back through the passage 83 into the chamber 22 where it is held under precompression until the piston has passed the 110 passage 83. Just previous to the piston having passed the passage 83 the exhaust valve has opened, permitting burning gases under expansion to escape and the piston continuing this outward stroke passes the 115 passage 83 when the valve controlling this passage 83 opens and permits gases that were precompressed in the chamber 22 to go through the passage 83 and drive out the residue of exhaust gas remaining in the 120 125 130

1
chamber 25. The next inward stroke of the piston again compresses the gas that has just entered the chamber 25 through the passage 83 were the same series of operations again takes place. It is to be noted that the same intake port is common to operation of the engine either as a four or two cycle.

The described cooling and cycle changing means are utilizable in every type of engine 10 whether of single or multiple unit construction, using a piston rod and not a connecting rod.

By changing the ratio of the gears 112 and 113 the structure may be made a permanent four or two cycle engine.

The invention is not limited to the specific form herein illustrated and described, but may be embodied in other forms without departure from its spirit as defined in the 20 following claims. It is intended that all matter contained in the above description or shown in the accompanying drawings shall be interpreted as illustrative and not in a limiting sense.

25 I claim:—

1. In an internal combustion engine, a cylinder comprising inner and outer cylindrical walls with an intermediate annular air chamber shut off from communication with the crank case and closed at both ends, a piston reciprocable in said cylinder, a piston rod connected with said piston and reciprocable through one end of the cylinder, a gland for said piston rod, said air chamber forming a precompression chamber, there being ports affording communication between the cylinder and air chamber at one end of the cylinder, and exits from said air chamber, there being a valve-controlled passage between the cylinder and said air chamber, to prevent communication therebetween during four-cycle operation.

2. In an internal combustion engine, a cylinder comprising inner and outer cylindrical walls with an intermediate annular air chamber shut off from communication with the crank case and closed at both ends, a

piston reciprocable in said cylinder, a piston rod connected with said piston and reciprocable through one end of the cylinder, 50 a gland for said piston rod, said air chamber forming a precompression chamber, there being ports affording communication between the cylinder and air chamber at one end of the cylinder, exits from said air chamber, there being a valve-controlled passage 55 between the cylinder and said air chamber, to prevent communication therebetween during four-cycle operation; said cylinder formed with lateral extensions with chambers communicating with the air chamber and the cylinder, and cam-controlled valves having stems working through the walls of said extensions and controlling said chambers.

3. In an internal combustion engine, a cylinder comprising inner and outer cylindrical walls with an intermediate annular air chamber shut off from communication with the crank case and closed at both ends, a 70 piston reciprocable in said cylinder, a piston rod connected with said piston and reciprocable through one end of the cylinder, a gland for said piston rod, said air chamber forming a precompression chamber, there 75 being ports affording communication between the cylinder and air chamber at one end of the cylinder; exits from said air chamber, there being a valve-controlled passage between the cylinder and said air chamber, to prevent communication therebetween during four-cycle operation, said cylinder formed with lateral extensions with chambers communicating with the air chamber and the cylinder, cam-controlled valves 80 having stems working through the walls of said extensions and controlling said chambers, said cylinder having lateral bosses, and tappet pins working through said bosses and interposed between the stems of said valves 85 and the cams.

In testimony whereof I have affixed my signature.

ROSCOE F. LEVENS
